DESIGN.

L. KAHN & R. THIEM.

COOKING STOVE.

No. 17,798.

Patented Oct. 18, 1887

UNITED STATES PATENT OFFICE.

LAZARD KAHN AND RUDOLPH THIEM, OF HAMILTON, OHIO, ASSIGNEES TO
F. & L. KAHN & BROTHERS, OF SAME PLACE.

DESIGN FOR A COOKING-STOVE.

SPECIFICATION forming part of Design No. 17,798, dated October 18, 1887.

Application filed August 2, 1887. Serial No. 215,982. Term of patent 7 years.

To all whom it may concern:

Be it known that we, LAZARD KAHN, a citizen of the United States, and RUDOLPH THIEM, a subject of the Emperor of Germany, both residents of Hamilton, Butler county, Ohio, have invented certain new and useful Designs for Stoves, of which the following is a specification, reference being had to the accompanying print forming a part hereof, which is a perspective view of a stove embodying our design.

The leading features by which our design is characterized are as follows: The closet-doors A are embellished by a rectangular panel having a concave elliptical center with a border-line, said elliptical center bearing the representation of an eagle holding branches in its talons, the branches projecting sidewise beyond the margin of the elliptical center and presenting leaves in the end portions of the rectangular panel. The closet-corners B are ornamented with fluted pilasters fancifully banded and terminating at their upper ends in representations of flames. The oven-door C is embellished by a rectangular panel having in its center a circular ornament, the panel portions to each side of the circular ornament bearing representations of cornucopias of fruits, flowers, and foliage, and margined by a molding of Gothic arches containing conventional leaves and bearing sprays of semi-clavate ornaments. The reservoir door D is embellished by a rectangular panel having a central circular ornament representing an animal-face, sprays of foliage being held in the mouth of the face and projecting sidewise from the circular ornament into and on the end portions of the rectangular panel. The ash-door F is embellished by a rectangular panel having a horizontal cross-bar swelled at its center into a circular ornament, the panel above and below the central ornament bearing representations of radiating leaves. The front door, G, is embellished at its center with a representation of a vase of fruit flanked by sprays of foliage. The central closet-flue, H, is embellished by a front panel bearing a representation of a fanciful vase with foliated handles and with a foliated double-scroll foot. The side brackets,

J, of the closet are embellished by representations of entwined vines and a climbing cupid. The base-brackets K of the closet have their fronts embellished by double-ended foliate scrolls. The skirting L is embellished by a representation of a porker centrally disposed on a foliate ornament flanked by extending foliate branches. The legs M are embellished by representations of leaf-work projecting inwardly from the edge of the legs, and by a centrally-disposed fanciful drooping leaf bearing at its top the representation of a sheep's head. The register N is embellished by sprays of foliated drooping over the register openings.

We claim—

1. The design for a stove herein shown and described, comprising the closet doors A, embellished by a rectangular panel having a concave elliptical center with a border-line, said elliptical center bearing the representation of an eagle holding branches in its talons, the branches projecting sidewise beyond the margin of the elliptical center and presenting leaves in the end portions of the rectangular panel, the closet having corners B, ornamented with fluted pilasters fancifully banded and terminating at their upper ends in representations of flames, the oven-doors C, embellished by a rectangular panel having in its center a circular ornament, the panel portions to each side of the circular ornament bearing representations of cornucopias of fruits, flowers, and foliage, the reservoir D, embellished by a rectangular panel having a central circular ornament representing an animal-face, sprays of foliage being held in the mouth of the face and projecting sidewise from the circular ornament into and on the end portions of the rectangular panel, the ash-door F, embellished by a rectangular panel having a horizontal cross-bar swelled at its center into a circular ornament, the panel above and below the central ornament bearing representations of radiating leaves, the front door, G, embellished at its center by a representation of a vase of fruit flanked by sprays of foliage, a central closet-support, H, embellished by a front panel bearing a representation of a fanciful vase with foliated han-

- dles and with a foliated double-scroll foot, the side bracket, J, of the closet, embellished by representations of entwined vines and a climbing cupid, the base-brackets K of the closet, having their fronts embellished by double-ended foliated scrolls, the skirting L, embellished by a representation of a porker centrally disposed on a foliate ornament flanked by extending foliate branches, the legs M, embellished by representations of leaf-work projecting inwardly from the edge of the legs and by a centrally disposed fanciful drooping leaf bearing at its top the representation of a sheep's head, and the register N, embellished by sprays of foliage drooping over the register-openings.
2. In a design for a stove, the closet-doors A, embellished by a rectangular panel having a concave elliptical center with a border-line, said elliptical center bearing the representation of an eagle holding branches in its talons, the branches projecting sidewise beyond the margin of the elliptical center and presenting leaves in the end portions of the rectangular panel, as shown.
3. In a design for a stove, the closet having its corners B ornamented with fluted pilasters fancifully banded and terminating at their upper ends in representations of flames, as shown.
4. In a design for a stove, the oven-door C, embellished by a rectangular panel having in its center a circular ornament, the panel portions to each side of the circular ornament bearing representations of cornucopias of fruits, flowers, and foliage bordered by the arch and clavate molding, as shown.
5. In a design for a stove, the reservoir D, embellished by a rectangular panel having a central circular ornament representing an animal-face, sprays of foliage being held in the
- mouth of the face and projecting sidewise from the circular ornament into and on the end portions of the rectangular panel, as shown.
6. In a design for a stove, the ash-door F, embellished by a rectangular panel having a horizontal cross-bar swelled at its center into a circular ornament, the panel above and below the central ornament bearing representations of radiating leaves, as shown.
7. In a design for a stove, the central closet-flue, H, embellished by a front panel bearing a representation of a fanciful vase with foliated handles, and with a foliated double-scroll foot, as shown.
8. In a design for stoves, the side brackets, J, of the closet, having double scrolls with foliated ends embellished by representations of entwined vines and a climbing cupid, as shown.
9. In a design for stoves, the base-brackets K of the closet, having their fronts embellished by double-ended foliated scrolls, and the intermediate panel, N, as shown.
10. In a design for stoves, the skirting panel having a marginal bead and ornamentation representing a porker centrally disposed on a foliate ornament flanked by extending foliate branches, as shown.
11. In a design for stoves, the legs M, embellished by representations of leaf-work projecting inwardly from the edge of the legs, and by a centrally-disposed fanciful drooping leaf bearing at its top the representation of a sheep's head, as shown.
